UNITED STATES PATENT OFFICE.

JOHN C. GOULD, OF CHICAGO, ILLINOIS.

FASTENER FOR THE MEETING-RAILS OF SASHES.

SPECIFICATION forming part of Letters Patent No. 442,178, dated December 9, 1890.

Application filed April 14, 1890. Serial No. 347,826. (No model.)

To all whom it may concern:

Be it known that I, JOHN C. GOULD, a citizen of the United States, residing in Chicago, in the county of Cook and State of Illinois, have invented a new and useful Improvement 5 in Sash-Fasteners, of which the following is a specification.

My object in this invention is to provide a self-locking sash-fastener which is at the same time durable, simple, and easy of manufacture.

The novelty of the invention will be fully understood from the accompanying drawings and the following description.

15 The drawings show at Figure 1 a vertical section of the meeting-rails of two window-sashes provided with my invention, the fastener being shown in the unlocked position. Fig. 2 is a plan of the fastener with the parts 20 in the same position as in Fig. 1. Fig. 3 is a plan showing the fastener locked, and Fig. 4 is a vertical section on the line 4 4 of Fig. 3.

In said drawings, A represents the meeting-rail of the lower sash, and B the like rail 25 of the upper sash.

C is a plate attached to rail A and supporting a pivoted latch D. This latch may be pivoted to said plate C in any suitable manner; but the construction which I prefer is 30 illustrated at Fig. 4, the latch being provided with a housing d, which carries a downwardly-projecting pivot d', and the plate C being provided with a hollow post c, into which said pivot d' extends. A spring E for operating 35 the latch encircles the pivot d' within the post c, one of its ends being secured in the post and the other in the pivot. By means of this spring the latch is rotated to the locking position automatically when it is released 40 from its detaining device now to be described.

When the latch is moved to the unlocked or open position, which is done by taking hold of the handle portion d² and rotating the latch d³ to the position shown at Fig. 1, the tooth d⁴ 45 on the under surface of the latch engages with a corresponding tooth c' upon the upper surface of the plate C as soon as the hand is withdrawn. In this manner the latch is automatically retained in the open position, as 50 indicated at Fig. 1, until the meeting-rails are brought together, when the plate F upon

55 rail B strikes the point d⁴ of the latch, which projects over the other sash-rail, and lifts the latch out of engagement with the tooth c'. As soon as this has taken place the latch is free to swing to the locking position under the power of the spring E.

I prefer to provide plate F with a raised ridge f, which will come in contact with the point of the latch, and upon which the latch 60 will ride while moving to the locking position. This ridge tapers down to the level of plate F, as shown. The latch is slotted, as at D', in order that it may pass to either side of the stationary guard G, borne upon the plate F, 65 and said guard is provided with an overhanging portion g, under which the part h of the latch will pass, and thus lock the sashes against vertical movement. The guard G affords opportunity to bring the meeting-rails 70 close together, as the slot D' of the latch can be made to bear against said guard and produce this effect. A stop s is provided to limit the opening movement of the latch. The post c of plate C fits the interior of the housing 75 d, so that the latch may rotate on said post and be held thereby closely in its proper position, and supplements the pivotal function 80 of the shaft or pivot d'. The housing d covers the parts and keeps out the dust.

I make the spring E the means of holding the swinging latch down upon the post of plate C and thus save the provision of a special fastening for that purpose. The spring is caused to perform this function by confining 85 its ends in the manner shown, the one end being secured in an opening in the side of the post c, which confines it against movement in either lateral or vertical direction, while the other end is secured in a dovetail 90 groove d⁵ in the end of stud d'.

I claim—

1. The sash-fastener consisting of a spring-actuated swinging latch moving horizontally and attached to one of the sash-rails, means 95 for detaining said latch in the open position with its point projecting over the other rail, and a projection or plate having a guard adapted to act with said latch in locking the sashes together, and also adapted to release the 100 latch from said retaining device, substantially as specified.

2. In a sash-fastener, a pivoted latch provided with a housing d and a pivot on the interior of said housing, in combination with a supporting-plate having a post to receive said pivot and enter said housing, and a spring actuating said latch and also serving to fasten the latch and plate together, substantially as set forth.
3. The sash-fastener consisting of the swinging pivoted latch and its supporting-plate, said latch being slotted, as D' , in combination with the plate F , having guard G , said guard G having the overhanging portion g , substantially as specified.
- 15 4. The combination of the pivoted latch D ,

slotted, as D' , and its supporting-plate, with plate F , having the ridge f and the guard G , substantially as specified.

5. The combination, in a sash-fastener, of a pivoted spring-latch D , having a tooth d^3 , ²⁰ and a supporting-plate having a tooth c' , engaging tooth d^3 to hold the latch open, both located upon one sash-rail, in combination with a plate upon the other sash-rail for releasing the engagement of said teeth, substantially as set forth.
